his Atty.

UNITED STATES PATENT OFFICE.

WILLIAM J. DAVIS, OF CHICAGO, ILLINOIS.

MILK-BOTTLE AND CAP.

1,279,288.

Specification of Letters Patent. Patented Sept. 17, 1918.

Application filed April 16, 1917. Serial No. 162,273.

To all whom it may concern:

Be it known that I, WILLIAM J. DAVIS, a citizen of the United States, and a resident of Chicago, in the county of Cook and State 5 of Illinois, have invented certain new and useful Improvements in Milk-Bottles and Caps, of which the following is a full, clear, and exact specification.

My invention is concerned with improvements in milk bottles and caps therefor, and is designed primarily to produce a bottle of the class described with a cheap and practical cap, so designed and constructed that when the cap is removed, the contents of the 15 bottle can be readily poured out without permitting them to come in contact with any portion of the bottle that has not been protected by the cap.

My invention is further concerned with 20 a bottle of the class described, provided with a cap so constructed that the air which would tend to be compressed in the hollow of the cap is released until the cap comes in contact with the mouth of the bottle and 25 the sealing is completed.

My invention is further concerned with a bottle having a novel bottom which is designed to be more easily washed by machinery than are the bottles heretofore used.

30 To illustrate my invention, I annex hereto to a sheet of drawings in which the same reference characters are used to designate identical parts in all the figures, of which—

Figure 1 is a central vertical section 35 through the bottle showing the cap in place;

Fig. 2 is a side elevation of the preferred form of the cap with a portion thereof broken away and in central section, to show the sealing cut;

40 Fig. 3 is a top plan view of the cap;

Fig. 4 is a central vertical section of a modified form of the cap;

Fig. 5 is a top plan view of the same; and

45 Fig. 6 is a view of the mouth without the cap.

The general shape of the body of the bottle *a* embodying my invention is that of the customary milk bottle, although it will be understood that the invention is not necessarily confined to bottles of this general shape. The bottom *b*, however, is differently designed in that the corners are rounded off by a considerable curve, and the center of 55 the bottom is occupied by the protuberance *c*, which it will be noted is connected by a

continuously concaved surface with the rounded corners, so that when a jet of water is directed into the center of the bottle, as occurs in some forms of bottle-washing machines, the jet of water will strike on the point of the protuberance *c* and be deflected along the concaved surfaces, thus washing out the bottom and the corners much more effectively than is possible where the center 60 of the bottom of the bottle is flat, as in that case, the water striking the bottle tends to rebound and does not necessarily flow into the corners. This, of course, is especially true where the bottles have the water thrown 70 into them in their inverted position, as is the general practice.

The mouth and neck of the bottle are substantially modified from the customary form, and the mouth proper has the high inner 75 annular flange *d* which is continuous with the general outline of the bottle, while the neck has thereon at a suitable distance below the top of the flange *d* an exterior flange *e*, which is separated from the flange *d* a 80 sufficient distance to make the deep and narrow annular channel *f*, which annular channel is adapted to receive the annular edge *g* of the cup-shaped cap *h*, which is of the proper size and thickness shown, so that 85 when the cap is forced down over the mouth of the bottle, as shown in Fig. 1, the edge *g* thereof will enter the recess *f*, and hold the cap securely in place against any accidental removal. These caps are principally 90 constructed of some vegetable fiber, such as pasteboard, straw-board, etc., and in the preferred form shown in Figs. 2 and 3, the annular walls of the cap are formed by corrugating and pressing them into shape from the flat disk from which the cap is formed.

In the modification shown in Fig. 4, the thickness of the edge *g* is secured by folding back an annular portion *j* of the cap, the two folds in this case being thick enough 100 to fill the channel. With the corrugated form shown in Figs. 2 and 3, the natural tendency of the folded portion to expand helps to keep the cap in place.

Where the interior of the cap is substantially cylindrical, necessitating a cylindrical exterior of the flange *d*, it becomes necessary to make some provision for the escape of the air that tends to be confined between the cap and the top of the contents of the 110 bottle, as soon as the edge of the cap is started in its downward movement over the

flange *d*, and for this purpose I preferably provide the semicircular cuts *k* at the proper point in the top of the cap, and when these cuts are made, the tongue *l* resulting therefrom is forced down into the interior of the cap enough so that there is a free passage for the air to escape as the cap is shoved down into place. These caps are preferably coated with paraffin, and it will be obvious that as the cap is rammed home, as it appears in Fig. 1, the outer end of the tongue *l* will engage the upper edge of the flange *d* and be forced up into its closed position, the paraffin acting as the sealing agent sufficiently to make the closure air-tight when the cap is in place.

With these caps having the cylindrical outline, it is possible to place them one above the other, without their nesting, in the supply tube of a bottle capping machine, whence they can be fed by a pushing stroke over the top of the bottle in the same manner as are the ordinary caps now in use.

To facilitate the removal of the caps from the bottle, and also to make sure that they cannot expand at the bottom sufficiently so as to overlap the top of the cap below in the supply pipe of a bottle capping machine, I may form the folded annular flange *m*, seen in Fig. 4, and it will be understood that with the thinner material shown in this form it is easier to form the flanges *m*.

While I have shown and described my invention as embodied in the form which I at present consider best adapted to carry out its purpose, it will be understood that it is capable of some modifications, and that I do not desire to be limited in the interpretation of the following claims, except as may be necessary to state the state of the prior art.

What I claim as new, and desire to secure by Letters Patent of the United States is:

1. In a bottle and cap, the combination with a bottle having an elongated, generally cylindrical exterior sealing surface just below its mouth, of a cap having an elongated interior sealing surface before it is applied, adapted to coöperate therewith, said cap having a tongue normally depressed to form an opening and cut in the flexible top of the cap directly over the edge of the mouth, so as to be engaged and closed thereby when it is brought in contact therewith.

2. In a bottle and cap, the combination

with a one-piece bottle having an elongated 55 cylindrical pouring flange terminating its neck, said flange having an annular sealing surface on its exterior face together with a comparatively short unyielding and immovable cap retaining flange outside of the base 60 of the pouring flange, said cap retaining flange having an annular inner surface parallel to the sealing surface and its top well below the top of the pouring flange for the purpose described, of an elongated cylindrical fibrous cap having its disk-like top adapted to rest on the top of the pouring flange and its annular bottom flange adapted to enter and be forced in it to close tightly by itself the entire annular recess formed 70 between the two flanges to hold the cap from expanding and secure it in place simply by a downward movement, and to be removed by a simple upward movement without destroying either the bottle or the cap.

3. The combination with a glazed bottle adapted for repeated use having a narrow high annular flange at its mouth over which its contents are poured without coming in contact with the second flange, and a second 80 annular cap-securing flange outside of the first and at a substantially lower level, the two flanges between them forming a narrow vertically disposed channel, the lower portion of which is the same width throughout 85 but narrower than the thickness of either flange and into which the edge of a cover enclosing the inner flange may be forced by a direct downward movement along the axis of the bottle, the top of the pouring flange 90 extending above the top of the cap-securing flange a distance greater than the thickness of either flange, of a slightly flexible fiber cap having a circular center and an annular side portion, the rim of which enters the annular channel and holds the cap securely in place and the bottle sealed without deforming either it or the bottle by engaging when seated both the outer wall of the inner flange and the inner wall of the outer flange, substantially as and for the purpose described.

In witness whereof, I have hereunto set my hand and affixed my seal, this ninth day of April, A. D. 1917.

WILLIAM J. DAVIS. [L. S.]

Witness:

JOHN HOWARD McELROY.
